DISTRIBUTOR BAR SAFETY FOR
TYPOGRAPHICAL MACHINESGeorge J. H. Sausele, New Providence, N.J., assignor to
Harris-Intertype Corporation, Brooklyn, N.Y., a cor-
poration of Delaware

Filed May 4, 1961, Ser. No. 107,789

3 Claims. (Cl. 199—43)

This invention relates to typographical machines of the general class wherein matrices are stored in magazines and selectively delivered therefrom by manipulation of a keyboard or in response to a code tape operating unit, assembled in a line for reproduction either by casting a type bar or by photography after which they are individually fed through a distributor and along a distributor bar from which they drop into their proper channels in the magazines, when their respective toothed combinations reach complementary notches in the distributor bar.

This invention is particularly adapted to typographical linecasting machines of the type wherein the upper ends of the channel entrance partitions are flexible. In such machines, distributor safety mechanism is provided whereby the distributor driving clutch will usually be disconnected whenever matrices failed to properly enter the channel entrance; however, this safety mechanism occasionally fails to operate quickly enough to prevent damage in the event of malfunctions such as "flat matrices" on the top of the distributor partitions and damaged tooth combinations. It occasionally happens that when a tooth combination of a matrix is damaged during transfer from the second elevator bar into the distributor box, the matrix does not drop from the distributor bar where it should and is carried on by the distributor screws until its teeth jam against a following combination on the bar whereupon the ears of the matrices are forced by the distributor screws and the matrix becomes damaged beyond repair.

According to the present invention the distributor bar is attached to the main frame fork of the composing machine by flexible mounts whereby it is capable of endwise movement but is spring biased in one direction against a fixed stop. The floating movement of which this arrangement is capable is utilized by attaching to the bar an arm which operatively engages an element of the existing safety mechanism in such manner that lateral movement of the bar of only a few thousandths of an inch will cause the distributor driving clutch to be disconnected.

In view of the foregoing, it is the principal object of this invention to provide a distributor safety mechanism which is particularly adapted to prevent matrix damage caused by malfunction of the distributor mechanism while matrices are being delivered thereby to their respective magazine channels.

Other objects and structural details of the present invention will be apparent from the following description when read in conjunction with the accompanying drawing wherein:

FIGURE 1 is a fragmentary elevational view, partly in section, of the rear of a typographical machine and shows the method of suspending the distributor bar, according to the present invention, and its relation to the existing distributor drive safety mechanism.

FIGURE 2 is a fragmentary plan view of the mechanism shown in FIGURE 1.

FIGURE 3 is an enlarged elevational view, in section, on line 3—3 of FIGURE 1 and shows a "flat" matrix resting upon the top of the channel entrance partitions and in relation to a matrix which has just been released from a point above it.

FIGURE 4 is a rear elevational view of the mechanism

2

shown in FIGURE 3 but with certain part removed for clarity of disclosure.

FIGURE 5 is a fragmentary perspective view showing the interconnection between the distributor bar of the present invention and the known distributor clutch tripping mechanism.

FIGURE 6 is an enlarged elevational view, partly in section, of a distributor-driving clutch.

FIGURE 7 is a schematic end view of the distributor feed screw drive gearing.

FIGURE 8 is an enlarged fragmentary view similar to FIGURE 1 but showing an alternative form of distributor bar suspension.

FIGURE 9 is a fragmentary end sectional view taken generally on line 9—9 of FIGURE 8.

FIGURE 10 is an enlarged perspective view of a matrix supported upon the teeth of a distributor bar.

Referring to FIGURE 6 which shows the existing clutch which is utilized in the present invention, a pulley 12 driven by a belt from the intermediate shaft of a line-casting machine (not shown) is rotatably mounted upon a shaft 14. Also mounted upon shaft 14 is a clutch flange 16 provided with a key 18 which fits into an elongated slot in clutch shaft 14 and will thereby be caused to rotate with shaft 14. This key and slot arrangement permits the flange to move endwise when the clutch is disengaged. A friction washer 20 is mounted between clutch flange 16 and pulley 12 and is normally held in frictional engagement between the flange and the pulley by compression spring 22 the tension of which may be varied by adjusting knob 24. Fixed upon the hub of flange 16 is a cam 26 having a plurality of cam surfaces the low dwells 28 of which are just clear of alignment with a pin 30 which extends upwardly from an arm 32 of rock shaft 34 which is pivotally mounted in the frame work (not shown) of the distributor frame. A reduced portion of the hub of flange 16 is rotatably mounted in a bearing 36, of the distributor frame, which thereby rotatably supports the clutch mechanism. Whenever shaft 34 is rocked in a counter-clockwise direction, as viewed in FIGURE 5, the pin 30 mounted in the arm 32 thereof will be raised into the path of one of the low dwells 28 and as the cam 26 rotates it will be forced to the left, as viewed in FIGURE 6, and thus force flange 16 to the left against the tension of spring 22 thereby breaking the driving connection through friction washer 20 thus causing rotation of shaft 14 to cease and pulley 12 to idle freely upon said shaft.

Referring to FIGURES 3, 6 and 7, the distributor screws 38, 40 and 42 are driven by gear 44 fast to shaft 14. As shown in FIGURE 7, gear 44 meshes with gears 46 and 48 attached to distributor screws 38 and 40, respectively, which are thereby caused to turn in the same direction to thus drive matrices along the distributor bar by engagement of their threads with the upper and lower forwardly extending ears of said matrices. Also fixedly mounted on the bearing end of distributor screw 38 is a gear 50 which meshes with a gear 52 fixedly mounted on the bearing end of distributor screw 42 which is thereby caused to rotate in a direction opposite to that of screws 38 and 40 and therefore, by engagement of its screw thread with the upper rearwardly extending ears of matrices will assist screws 38 and 40 to drive matrices along the distributor bar at right angles to the direction of travel.

Referring particularly to FIGURE 5, the existing distributor safety mechanism, with which the present invention cooperates, comprises a horizontally disposed comb bar 54 having a plurality of forwardly extending tines 56, one for each flexible channel entrance partition 58 of channel entrance 59 (FIGURE 3) and disposed in close proximity on one side of each of the upper ends of said partitions. Also carried on rock shaft 34 is an

upwardly extending arm 69 which is biased by a spring 61 in a counterclockwise direction, as viewed in FIGURE 5, and has mounted thereon an angle piece 62 which is adjustable lengthwise. Projecting from the left-hand end of comb bar 54 is an arm 64 which engages the free lip of angle piece 62 thus enabling latching of rock shaft 34 in a clockwise direction against the resistance of spring 61 and thereby positioning clutch disengaging pin 30 out of range of cam 26 thus permitting free rotation of the distributor screws to drive matrices along the distributor bar.

According to the foregoing mechanism, when matrices fail to enter, properly, between the flexible channel entrance partitions 58, a following matrix driven along the distributor bar will engage the protruding matrix or matrices which will then be driven against the upper portion of an adjacent partition 58 which will thereby be flexed against its corresponding tine 56 of comb bar 54 which will thereby be moved to the left thus displacing arm 64 from engagement with the free end of angle piece 62 whereupon spring 61 will cause shaft 34 to rock in a counterclockwise direction and thereby shift pin 30 into alignment with one of the cam surfaces 28 to disconnect the distributor driving clutch.

According to the present invention a pair of brackets 66 and 68 are attached to the distributor bracket 70 of a linecasting machine and a pair of flat-spring hangers 72 and 74 are suspended from said brackets 66 and 68. Attached to the lower ends of hangers 72 and 74 is a pair of angle brackets 76 and 78 to which is attached a toothed distributor bar 80. A tension spring 82 is provided between bracket 76 and an adjustable hook on distributor bracket 70 to resiliently hold the distributor bar to the right, as viewed in FIGURE 1, against a fixed stop 84 to assure proper relationship between the various tooth combinations of the distributor bar and their respective channel entrance partitions. Because of the flat spring construction of the distributor bar supporting hangers the distributor bar is restricted against sidewise movement and is free to move lengthwise a sufficient amount to cause disengagement of the clutch.

As best shown in FIGURE 5 distributor bar 80 is provided at its left end, as viewed from the rear of the machine, a compound-angle bracket 86 the free extremity of which abuts an upstanding block 88 attached to comb bar 54; thus, slight horizontal movement of distributor bar 80 to the left will cause the same disconnection of the distributor bar clutch, shown in FIGURE 6, as would be caused by flexing of the partitions 58.

FIGURES 8 and 9 show another embodiment of the present invention. It should be noted at this point that FIGURE 8 is a view somewhat similar to FIGURE 1 but taken from the opposite side of the distributor bracket 70. According to this embodiment, the distributor bar 80 is suspended on roller bearings supported upon studs 90 and 92 which are rigidly supported in the distributor bracket 70 as shown in FIGURE 9. According to this embodiment the inner race 94 of each bearing is locked against rotation by jamming it between a pair of washers against distributor bracket 70 by a nut 96. Attached to the bar 80 is a pair of mounting blocks 98 and 100 each having a slot in the upper edge thereof which slot is covered by caps 102 and 104 respectively to form an opening in which the outer race 106 of the bearing is snugly but rotatably fitted. Thus, the weight of the distributor bar 80 is supported through bearings by the caps 102 and 104 respectively. As in the first embodiment, the distributor bar is spring biased in a direction away from the distributor driving clutch (to the left as viewed in FIGURE 8), but, in the present instance, this movement is limited by an adjustable stop screw 107 mounted in block 100 and engaging the periphery of the adjacent outer bearing race 106.

Operation

As may be noted in FIGURE 10 the distributor bar teeth 108 are notched at various points and the combination teeth 110 of matrix 112 are cut away so that when a matrix reaches a point on the distributor bar where the notching of said bar and said matrix are complementary, the matrix will gravitate into the channel entrance 59 provided no interference exists such as the flat matrix shown in FIGURE 3 or the matrix tooth combinations are damaged to such an extent that the matrix is frictionally retained on the distributor bar. As a point of information, a matrix will occasionally land upon the upper edge of a partition 58 and be thereby caused to fall flat across the partitions as shown in FIGURES 3 and 4.

When a matrix is released from the distributor bar and engages a flat matrix resting across the top of a group of partitions, as shown in FIGURE 4, the tooth combinations do not clear each other and the ears of the matrix remain in contact with the distributor screws which continue to drive it along against succeeding combination teeth of the distributor bar which, by virtue of its floating action, will be forced to the left as viewed in FIGURE 5, whereupon its depending arm 86 will engage block 88 of comb bar 54 which will be thereby caused to move to the left thus displacing its latching arm 64 from engagement with angle piece 62 whereupon spring 61 through arm 60 will cause shaft 34 to be rocked in a counterclockwise direction and drive pin 30 into the field of one of the low dwells 28 of rotating cam 26 which will be thereby forced to the left as viewed in FIGURE 6 to break the driving connection between driving pulley 12 and distributor screw driving shaft 14 thus stopping rotation of the distributor screws before damage can be inflicted upon the interfering matrix or the teeth of the distributor bar 80.

In the event that a damaged matrix fails to release from the distributor bar the safety action of the present invention would be implemented in the same manner just described.

After the interference has been cleared the distributor drive may be reactivated by pushing rest lever 114, extending rearwardly from rock shaft 34, in a clockwise direction, as viewed in FIGURE 5, whereby pin 30 will be withdrawn from engagement with cam 26 thus reactivating the drive connection between pulley 12 and distributor drive shaft 14. Simultaneously with the actuation of rest lever 114, arm 64 of comb bar 54 will reengage angle piece 62 to lock pin 30 in its inactive position as shown in FIGURE 5.

While there is above described but two embodiments of the present invention it is possible to produce still other embodiments without departure from the inventive concept above disclosed and it is, therefore, desired that only such limitations shall be imposed on the appended claims as are stated therein, or required by the prior art.

What is claimed is:

1. In a linecasting composing machine for assembling and distributing a plurality of classes of matrices, means for selectively releasing matrices from their magazine storage channels for assembly in a line prior to presentation before a slotted mold in which a slug is cast against the line of assembled matrices; a plurality of rotatable distributor screws for returning said matrices to their respective magazine channels; means for presenting said matrices, seriatim after casting, to said distributor screws; means for driving said screws; a clutch between said driving means and said screws; a distributor bar suspended between said distributor screws and having a plurality matrix tooth combinations, one for each matrix storage channel, the distributor bar suspending means being adapted to permit lengthwise movement of said bar; and means operatively responsive to lateral movement of

said bar to cause disconnection of said distributor screw driving clutch.

2. A combination according to claim 1, whereby the distributor bar suspending means comprises a pair of flat springs and said distributor bar is resiliently urged by a tension spring in one direction against a fixed stop and said bar is adapted when an interference occurs between the combination teeth of a matrix and the combination teeth of said distributor bar, while said matrix is being driven along said distributor bar by said distributor

screws, to be shifted away from said stop and operatively cause disconnection of said distributor screw driving clutch from said distributor driving means.

3. A combination according to claim 1 whereby the distributor bar suspending means comprises a pair of rollers pivotally attached to the main frame work of said linecasting machine.
